(57) **CLAIM**

The ornamental design for a lock escutcheon, as shown and described.

DESCRIPTION

The claimed decorative lock escutcheon is intended to cover the keyhole of a lock on a casket or the like.

FIG. 1 is a front view of a lock escutcheon showing our new design.

FIG. 2 is a left side view thereof.

FIG. 3 is a right side view thereof.

FIG. 4 is a top plan view thereof.

FIG. 5 is a bottom plan view thereof; and,

FIG. 6 is a back view thereof.

1 Claim, 1 Drawing Sheet

FIG. 6

FIG. 3

FIG. 1

FIG. 2

FIG. 4

FIG. 5
